UNITED STATES PATENT OFFICE.

HANS M. HANSON, OF MASON CITY, IOWA.

CONVEYER.

Application filed July 12, 1923. Serial No. 651,125.

To all whom it may concern:

Be it known that I, HANS M. HANSON, a citizen of the United States, residing at Mason City, in the county of Cerro Gordo 5 and State of Iowa, have invented a new and useful Conveyer, of which the following is a specification.

This invention has reference to conveyers and more particularly to a conveyer especially designed to facilitate the unloading 10 of freight cars or the like, wherein heavy articles are being unloaded.

The primary object of the invention is to provide a device of this character which 15 may be readily and easily moved from place to place novel means being provided for moving one of the sections of the loader into and out of operation.

A further object of the invention is to 20 provide a conveyer which will be supported throughout its length to eliminate sagging of the container, to retard the movement thereof while in operation.

With the foregoing and other objects in 25 view which will appear as the description proceeds, the invention resides in the combination and arrangement of parts and in the details of construction hereinafter described and claimed, it being understood that 30 changes in the precise embodiment of the invention herein disclosed, may be made within the scope of what is claimed, without departing from the spirit of the invention.

35 Referring to the drawings:

Figure 1 is a side elevational view of a conveyer constructed in accordance with the invention.

Figure 2 is a vertical sectional view there- 40 through.

Figure 3 is a sectional view taken on line 3—3 of Figure 1.

Figure 4 is a plan view of the conveyer.

Referring to the drawings in detail, the 45 conveyer includes a supporting frame comprising vertical end bars 5 and 6 which bars are connected by the horizontally disposed bars 7.

50 Adjacent to the upper ends of the bars 5 and 6 are inclined bars 8, the bars 6 being relatively long as compared with the bars 5 to support the bars 8 at angles.

At the upper ends of the bars 5 and 6 are arranged bearings 9 which bearings support

the shafts 10 that support the conveyer 9' 65 the ends of the shafts being disposed therein. Mounted on the shafts 10 are sprocket wheels 11 over which the chains 12 move, the chains being however connected by the rods 13 that are secured thereto in any suitable and well known manner. On these rods 13 are rollers 14 which rollers move over the trackways 15 to support the weight of the material on the conveyer.

The forward shaft 10 is relatively long 65 and supports a sprocket wheel 16 on its outer end, which receives motion from the power shaft 17, through the chain 18 that moves over sprocket 19 mounted on one end of the shaft 17.

The opposite end of shaft 17 is also supplied with a sprocket 20 that accommodates the chain 21 that moves over the sprocket 22 carried at one end of the rotor shaft 23 of the motor 24, so that rotary movement may 70 be imparted to the shaft 23 to operate the shafts associated therewith.

Supported by the bars 5 and 6 are trackways 25 in which the side rails 26 of the extensible conveyer section 27 are positioned, 80 the lower edges of the side rails 27 being supplied with rack bars 28. Cooperating with the rack bars are gears 29 mounted on the shaft 30 that is supported in suitable bearings formed in the bars 6, there being 85 provided a handle 31 on one end of the shaft to rotate the shaft to cause the extension to be moved towards or away from the body portion.

At the ends of the extensible conveyer 90 section 27 are mounted shafts 33 that have their ends disposed in suitable bearings formed in the guide bars in the extensible section. Sprockets 34 are mounted on the ends of the shafts 33 and accommodate the 95 chain 35. This chain 35 also moves over the sprocket wheel 37 mounted on the shaft 17 to receive motion therefrom, the chain 35 also passing over idle sprockets 38 whereby movement of the shaft 17 is imparted to the 100 conveyer 36.

From the foregoing it will be obvious that the device may be readily and easily moved to a position adjacent to a car or the like to be unloaded, whereupon the conveyers operate, to the end that material positioned on the conveyer 9' will be moved forwardly and dropped on to the conveyer 36 from

where the material may be deposited in a wagon or other vehicle being loaded.

A movable plate 39 is pivotally supported at the forward end of the conveyer 36 and 5 is held in position by means of the brace rod 40 so that material discharged at the outer end of the conveyer 26 will drop onto the plate 39 and be discharged into the wagon or vehicle positioned under the other end of 10 the conveyer 26.

What is claimed as new is:—

1. In combination with a fixed conveyer, an extension conveyer comprising a frame 15 slidably mounted adjoining said fixed conveyer; a fixedly supported drive means for both said conveyers, an endless conveying element mounted on said slidably frame and having one run thereof looped away from said frame and about said fixed driving 20 means, and means situated in the space provided by the looping of said conveying ele-

ment and cooperating with said frame to slide the same back and forth.

2. In combination with a fixed conveyer, an extension conveyer comprising a frame 25 slidably mounted adjacent the fixed conveyer, a conveying element carried by said slidably frame and having a portion thereof looped downwardly away from said frame, a fixed drive means engaging the looped 30 portion of said conveying element and having connection to drive said fixed conveyer, a rack bar on the lower portion of said slidably frame, and pinion means mounted within the space provided by the looping of said 35 conveying element and meshing with said rack bar for moving the slidable frame back and forth.

In testimony that I claim the foregoing as my own, I have hereto affixed my signature.

HANS M. HANSON.
